UNITED STATES PATENT OFFICE.

DANIEL W. MARTIN, OF LUFKIN, TEXAS.

CAR-REPLACER.

1,134,212.

Specification of Letters Patent.

Patented Apr. 6, 1915.

Application filed April 25, 1913, Serial No. 763,672. Renewed December 18, 1914. Serial No. 877,973.

To all whom it may concern:

Be it known that I, DANIEL W. MARTIN, a citizen of the United States, residing at Lufkin, in the county of Angelina and State of Texas, have invented a new and useful 5 Car-Replacer, of which the following is a specification.

The device forming the subject matter of this application is adapted to be employed 10 for derailing railway vehicles and for restoring derailed railway vehicles to the track.

The invention aims to provide a structure 15 of the type described which will readily and efficiently move the wheel of the railway vehicle laterally, and deposit the same either on or off the rail with a minimum amount of jar.

It is within the scope of the invention to 20 improve generally and to increase the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of invention herein disclosed can be made within the 30 scope of what is claimed without departing from the spirit of the invention.

In the drawings:—Figure 1 shows in perspective, one member of the structure; Fig. 35 2 shows in perspective, the other member of the structure; Fig. 3 is a transverse section on the line 3—3 of Fig. 1 showing the member depicted in Fig. 1, mounted on the rail; Fig. 4 is a top plan of the member shown in 40 Fig. 1.

Referring particularly to Figs. 1 and 4, the member 1 preferably comprises a hollow metallic body 2, suitably reinforced within its interior. The upper face of the 45 body 1 is bulged upwardly, or curved, as shown at 3. Mounted upon the face 3 is a rib which is denoted generally by the numeral 4. The rib 4, as an entity, is inclined from its ends to its intermediate portion, 50 toward the longitudinal center of the body 2. The rib 4 comprises arms 5 terminating in extensions 6 which meet at an angle denoted by the numeral 7. The angle defined by the extensions 6 is more acute than the 55 angle which the arms 5 would form if prolonged to a meeting point. The angle 7 is

located adjacent the intermediate portion of an upright edge 8 of the body 2. The edge 8 is inclined from its ends to its intermediate portion, toward the longitudinal center 60 of the body 2. Located upon the curved upper face 3 of the body 2, and relatively near to the ends of the body 2 are lugs 9 having functions which will be set forth hereinafter.

Formed integrally with the body 2 or otherwise secured thereto, and located adjacent the edge 8 is a depressed deck 10, the body 1 being cut away adjacent the ends of the deck 10, as indicated at 11. The free 70 edge of the deck 10 is provided with a depending flange 12, adapted to engage over the ball of the rail 14, as clearly shown in Fig. 3. Located in the angle defined by the upper face of the deck 10 and by the vertical edge 8 of the body 2 is a boss or lifting block 15, the upper surface of which is bulged upwardly or curved, as indicated at 16.

In order to derail a vehicle, the member 1, only, is employed. Referring to the derailing functions of the member 1, suppose that the operator is facing in the direction of the arrow A in Fig. 1 and that the member 1 is applied to the left hand rail. Then 85 the member 1 will project between the rails. Suppose that a car is moving along the track in the direction of the arrow A. The wheel of the car first rides upon the curved face 90 3 of the body 2, and the flange of the wheel is engaged by one arm 5 of the rib 4, the flange of the wheel being directed by the arm 5 against the corresponding extension 6. The extension 6 deposits the wheel upon the boss or lifting block 15 and the wheel 95 rides off the lifting block 15 onto the deck 10. The flange of the wheel is then engaged by the curved edge 8 of the body 1 and is carried laterally, the wheel in this manner being moved off the rail.

Suppose that it is desired to replace a derailed car or vehicle upon the track. Under such circumstances, let it be supposed the operator is facing in the direction of the arrow B. Then the member 1 is applied to the left hand rail and extends outside of the left hand rail. The member 17 is applied to the right hand rail and projects between the rails.

The member 17 is, for the most part, a 110 duplicate of the member 1, the parts already described in connection with the member 1,

being designated in the member 17 by corresponding numerals with the suffix "a". The member 17, however, differs from the member 1 in two particulars. First, the extensions 6^a are shortened and preferably there is a space between their inner ends, as shown at 18, the ends of the parts 6^a being set back from the edge 8^a of the body. Preferably, the boss or lifting block 15^a is provided 10 with an upstanding guide 19 which projects beyond the ends of the boss.

When it is desired to restore a vehicle to the rails, and referring to the left hand side of the vehicle, it will be understood that the 15 wheel first rides on to the curved face 3 of the member 1, the flange of the wheel being engaged by the arm 5 and being directed thereby against the extension 6, the extension 6 depositing the flange of the wheel 20 upon the curved face 16 of the lifting block 15. As the flange of the wheel rides downwardly off one end of the lifting block 15, the flange will be engaged by the curved 25 edge 8 of the body 2 and thereby will be deposited inside of the left hand rail.

In connection with the member 17 and referring to the right hand rail, the operation above described in connection with the member 1 takes place substantially without 30 alternation, saving as follows. The outer face of the wheel is engaged by the guide 19 and the wheel is thus held against laterally, outward movement, so that the flange of the wheel will be deposited inside the 35 right hand wheel. Noting the fact that the

ends of the extensions 6^a are set back from the edge 8^a, it will be seen that the flange of the wheel will not be crowded laterally to too great an extent but will ride readily into a position inside the right hand rail. 40

It is entirely obvious from the construction shown in the drawings, that the members 1 and 17 will exercise their functions when the vehicle is moving in either direction. 45

The function of the lugs 9 is to guide and replace the flangeless or blind driver of a locomotive engine.

Having thus described the invention, what is claimed is:— 50

In a device of the class described, a body having a sloping upper face and provided along one of its upright edges with a depressed deck which projects beyond said edge of the body and is provided in its under face with a rail receiving recess, there being a lifting block formed integrally with the deck and connected with said edge of the body, the lifting block extending laterally beyond a vertical plane passing through the 55 longitudinal center of the rail receiving recess. 60

In testimony that I claim the foregoing as my own, I have hereto affixed my signature in the presence of two witnesses.

DANIEL W. MARTIN.
